WALL TYPE HEATER

Noel E. Blazer, Berkeley, Calif., assignor to Westinghouse Electric Corporation, East Pittsburgh, Pa., a corporation of Pennsylvania

Application April 6, 1949, Serial No. 85,915

4 Claims. (Cl. 219—34)

1

My invention relates to a wall type heater, that is, a heater positioned in a recess or an opening in a wall.

The object of the invention is to minimize the deposit of particles of matter on the wall above the heater. Such deposit is commonly known as smudging.

In accordance with my invention, I provide a deflector which is disposed adjacent to but spaced from the top wall of the heater casing and the top of the frame, and which also projects beyond the front face of the heater. This deflector provides, together with said top wall and the top of the frame, a passage for free flow of cooler air continuously to and a little beyond the front face of the heater, and the deflector also directs the hot air away from the heater and the wall. The deflector projects from the front face of the heater a sufficient extent to keep the relatively hot and relatively cool air streams separated until they have attained substantially vertical direction of flow.

These and other objects are effected by the invention as will be apparent from the following description and claims taken in connection with the accompanying drawings, forming a part of this application, in which:

Fig. 1 is a perspective view showing the heater mounted in a wall;

Fig. 2 is a vertical section taken on the line II—II of Fig. 1;

Fig. 3 is a section taken on the line III—III of Fig. 2, looking upwardly; and,

Fig. 4 is a fragmentary front elevational view, showing the passage for the cooler air provided by the deflector.

The heater is of the wall or wall insert type and is shown on the drawing as disposed mainly but not entirely within a recess 10 provided in the wall 11. The heater is provided with an outer casing 12 which includes a rear wall 13, side walls 14, an inclined top wall 15 and a bottom wall 16. It further includes an inner casing or deflector 17 provided with a rear wall 18, side walls 19, a bottom wall 20 and an inclined top wall 21, said walls being disposed in spaced relation to the corresponding walls of the outer casing 12. The heating means is disposed within the inner casing. It comprises a heating element 22 which is supported upon the bottom wall 20 of the inner casing or deflector 17 and having a passage 24 communicating with a registering opening in the bottom wall 20.

A frame 25 extends around the front of the casing 12. This frame has a front wall 26, an

inner wall or flange 27 extending slightly inwardly of the casing 12, and an inclined outer wall or flange 28, the edge of which abuts against the face of the wall 11. A grille or grille panel 31 extends across the front face of the heater, and is disposed within and mounted on the frame 25 by means of pins 32 and spacer bushings 33. The grille 31 is thus a unit with, and is removable with, the frame 25. The frame is secured in place in any suitable manner, such as by screws 34.

In accordance with my invention, I provide the deflector 35 which comprises a short horizontal portion disposed on top of the grille 31 and secured between said top and the spacer bushings 33. The deflector further comprises an inner inclined portion 36 which extends along but spaced from the inclined top wall 15 of the outer casing, and it further includes an inclined outwardly projecting portion 37. As will be noted from the drawings, particularly Fig. 2, there is thus provided a passage 38, which extends first between the deflector portion 36 and the top wall 15, then between the horizontal portion of the deflector and the inner flange 27 of the frame and then between the outer deflector portion 37 and the front wall 26 of the frame.

The supply of electric current to the heating element is controlled by any suitable means, the details of which form no part of this invention.

Operation

The flow of air is indicated by the arrows on the drawing and will be clear therefrom. Air enters through the openings in the lower portion of the grille 31 and is discharged therefrom through openings in the upper portion of the grille. A major portion of the air enters through the lower portion of the grille into the space between the outer and inner bottom walls 16 and 20. Some of this air passes through the openings in the bottom wall 20 and the heating element, and provides the hottest stream of air. The heated air discharged from the top of the heating element is deflected by the inner wall 21 and is discharged through openings in the adjacent portion of the grille 31. Another stream of air enters the openings in the grille above the inner bottom wall 20, flows upwardly in contact with the heating element 22 and is heated thereby, and then mixes with the heated air leaving the interior of the heating element. Another portion of the air entering the space between the walls 16 and 20 passes upwardly through the space between the inner and outer

rear walls and this air stream remains relatively cool as it does not pass in contact with the heating unit. This air stream serves to cool the inner casing. A portion of this air stream passes through the passage between the inner top wall 21 and the baffle 36 and is mixed to some extent with the hot air leaving the heating unit. Thus, a relatively hot air stream is discharged through the upper openings in the grille 31.

Another portion of the relatively cool air passing between the rear walls passes through the above-mentioned passage 38 beginning with the space between the baffle 36 and the outer top wall 15. As this relatively cool air stream is discharged from the space between the deflector portion 37 and the front wall 26 of the frame, its direction has been changed to substantially vertical upward direction. The relatively hot air discharged through the openings in the upper portion of the grille 31 is deflected outwardly away from the wall by the projecting portion 37 of the deflector, and then flows upwardly in parallel with the relatively cool air stream. The relatively cool air stream provides a blanket which separates the hot air stream from the wall and thereby minimizes the deposit of particles on the wall.

An important characteristic of the deflector is that the outwardly projecting portion 37 projects outwardly a sufficient distance to permit the cool air stream to attain a substantially vertical direction before it is able to mix with the hot air stream. In this way, the air streams are caused to flow upwardly in parallel with a minimum of mixing and turbulence. To this end, the deflector portion 37 projects outwardly a distance at least as great or preferably greater than the minimum width of the passage 38, namely, the space between the horizontal portion of the deflector and the adjacent flange 27. In one embodiment of the present invention, the width of the spacing between the horizontal portion of the deflector and the adjacent flange 27, as determined by the spacer bushings 33, is $\frac{3}{16}$ inch.

Another characteristic of the deflector is that it extends inwardly a sufficient distance to divide the air going into the passage 38 before the air flowing below the deflector mixes with the hot air below the inner top wall 21.

While I have shown my invention in but one form, it will be obvious to those skilled in the art that it is not so limited, but is susceptible of various changes and modifications without departing from the spirit thereof.

What I claim is:

1. A heater of the wall insert type comprising a casing having rear, side and top walls and having substantial open area in the front face, a heating element disposed within the casing, a partition or deflector disposed between the heating element and the rear and top walls and spaced from the latter to shield the latter from the heat of the heating element and also to provide therewith a passage for relatively cool air, and a deflector extending inwardly of said casing between said top wall and said partition to provide a passage above the deflector for rela-

tively cool air and including a portion projecting forwardly of the forwardmost portion of the heater above the deflector a distance at least as great as the minimum width of the last-mentioned passage, said projecting portion thereby serving to deflect the hot air away from the front face of the heater and to maintain the hot and the relatively cool air streams divided until the latter attains substantially vertical flow.

2. A heater as set forth in claim 1 and further including a grill extending across the front face of the heater, said deflector being attached to and carried by said grill adjacent the top thereof and removable therewith as a unit.

3. A heater of the wall insert type comprising an outer casing having rear, side and bottom walls and an outwardly inclined top wall, an inner casing having a rear, side and bottom walls and an outwardly inclined top wall, the walls of the inner casing being disposed in opposed but spaced relation to the corresponding walls of the outer casing, a heating element disposed within the inner casing, said inner and outer casings having substantial open areas in the front face of the heater, and an air deflector comprising a portion extending parallel to but spaced from the inclined top wall of the outer casing and another portion extending to a point beyond the front face of the heater, the outer edge of said deflector being spaced horizontally from the forwardmost portion of the heater above the deflector a distance at least equal to the minimum width of the passage above the deflector.

4. A heater of the wall insert type comprising an outer casing having rear, side and bottom walls and an outwardly inclined top wall, an inner casing having a rear, side and bottom walls and an outwardly inclined top wall, the walls of the inner casing being disposed in opposite but spaced relation to the corresponding walls of the outer casing, a heating element disposed within the inner casing, said inner and outer casings having substantial open areas in the front face of the heater, a frame disposed about the open front face of the outer casing, a grille disposed within and attached to said frame and extending across the front face of the heater, a deflector disposed on top of and attached to said grille and extending inwardly and outwardly from the grille, said deflector being spaced from the outer inclined top wall and the frame to provide with them a passage for relatively cool air, and to deflect the heated air flowing below said deflector.
